UNITED STATES PATENT OFFICE.

CHARLES H. RUDD, OF EVANSTON, ILLINOIS, ASSIGNOR OF ONE-HALF TO JAMES W. WHITE, JAMES CLARENCE WHITE, AND HENRY M. LEWIS, TRUSTEES, ALL OF PHILADELPHIA, PENNSYLVANIA.

APPARATUS FOR ELECTRIC-RAILWAY SIGNALING.

SPECIFICATION forming part of Letters Patent No. 426,395, dated April 22, 1890.

Application filed October 28, 1889. Serial No. 328,442. (No model.)

To all whom it may concern:

Be it known that I, CHARLES H. RUDD, a citizen of the United States, residing at Evanston, in the county of Cook and State of Illinois, have invented certain new and useful Improvements in Apparatus for Electric-Railway Signaling, of which the following is a specification.

My invention relates to that class of electric railways in which the rails serve as conductors for electric currents operating a motor on the car, the current passing through which is regulated from the main or generating station.

15 The objects of my invention are not only to control the locomotive from the station, but automatically to indicate its speed and location at any given moment to the engineer at the generating or controlling station. These 20 ends I attain by using a track composed of three rails, insulated from each other in well-known ways, one of which rails acts as a conductor for the actuating or propelling current, which passes through the motor and 25 then returns to the generator through the other two rails, being alternately and automatically shifted from one to the other while passing through the motor, and actuating suitable well-known recording mechanism to 30 indicate at the controlling-station the speed and location of the locomotive.

The subject-matter of this invention is hereinafter designated in the claims at the close of this specification.

35 The accompanying drawings represent so much of an improved apparatus embodying all my improvements as is necessary to illustrate the subject-matter herein claimed.

Unless otherwise designated the devices 40 mentioned are of usual well-known construction, my invention not consisting so much in details of construction as in novel organizations and combinations of instrumentalities.

Figure 1 represents a plan view of the rail-way and motor, the generator, indicator, and circuit-connections being diagrammatically indicated. Fig. 2 represents a sectional elevation of the rails and motor, and Fig. 3 a perspective detail of the insulated collar and

bearing-spring forming the connection between the motor and supporting-wheel axle. Figs. 4 and 5 are views respectively similar to Figs. 1 and 2, showing another organization of the motor-circuit-shifting gearing and its connecting mechanism. Fig. 6 shows a 55 diagram illustrating the circuit-connections, and showing the details of the indicator-actuating apparatus. Fig. 7 is a plan showing another organization of the motor-circuit-shifting apparatus, and Fig. 8 a side view of 60 the motor-wheel with one of its side plates removed to show the details of the motor enclosed therein.

The drawings show my invention as applied to what is known as a "three-rail system," all 65 three rails being properly insulated from the earth and from each other in well-known ways, the central rail being shown therein as constituting the direct actuating, propelling, or motor circuit and the outer rails the return-circuit. The circuit passes from a suitable generator A at the central controlling main station through a conductor b to the central rail B, along which it passes to a motor-wheel C of usual well-known construction—such, for instance, as that shown and described in Letters Patent No. 259,589, granted to me June 13, 1882, in which a divided tire or commutator is employed. The darts in Fig. 1 show the course of the current. 70 The motor-wheel is shown as consisting of two circular metallic side plates or disks clasping between them a rim or felly of wood or other suitable insulating material projecting circumferentially beyond their peripheries, so as electrically to insulate them and the fixed metallic axle D, around which they 75 freely turn, from the rail. The rim is encompassed by a tire composed of separate sections insulated from each other, as shown at 1 2 3 4, Fig. 8. Electro-magnets C', corresponding in number with the tire-sections, are secured between the side plates radially to the axle, on which an armature d is fixed on one side, so that the inner poles of the 80 magnet pass close thereto. A wire c' connects each section of the tire with one terminal of its appropriate magnet-coil, the op-

posite terminal being connected by a wire c^2 with one of the side plates. This motor-wheel revolves loosely on an axis D, of brass or other suitable non-magnetic metal, with 5 which it is in electrical contact and through which the current passes to the frame E of the motor, the axle being firmly fixed in the frame. A supporting-axle F turns freely in suitable bearings in the other end of the motor-frame, which bearings are suitably insulated from the frame, as shown at f , Fig. 2. The supporting-axle F is likewise transversely divided into two sections F F', mounted in proper bearings and insulated 10 from each other, as shown at S', Fig. 1. Supporting-wheels G G', being plain metallic wheels of ordinary construction mounted on the respective ends of this axle and turning therewith, run, respectively, upon the rails 15 H H'.

Metallic springs P P', in electrical connection with the motor-frame, bear at their free ends upon commutator collars or rings I I' on the respective sections of the supporting- 20 axle F. These collars I I' are provided with insulating-segments $i i'$, encircling rather less than one-half their circumference and set opposite each other, so that the current from the motor-frame is alternately sent first 25 through one of the rails H H' and then through the other. These rails at the controlling-station are respectively connected by wires h h' with an electro-magnet J, consisting of two spools or poles j j', the armature J^2 of 30 which magnet is caused to rock on its pivot in a well-known way by the return-current, as hereinbefore explained, so as to operate an alarm, indicator, or signal device by means of a well-known clock-escapement 35 movement or in other well-known ways, so as to indicate to the engineer at the controlling-station the location and speed (each or all) of the locomotive. The current passes from the magnet by a wire k to the generator 40 A, thus completing the circuit. Fig. 6 shows the coils of the magnet J connected to this return-wire k, and are so wound that the breaks in the current cause the magnets to be alternately energized, consequently rocking the 45 armature J' of the magnet on its pivot j. This armature carries at its opposite end a forked arm provided with pawls or pallets actuating a ratchet or escapement wheel J^2 , mounted on a shaft carrying an actuating, registering, or 50 indicating mechanism of well-known construction. The rapidity of the vibrations of the armature indicates the speed of the locomotive, while their number on the register indicates its position.

60 The apparatus shown in Figs. 4 and 5 differs from that hereinbefore described only in the arrangement of the gearing upon the motor for shifting the circuit. A worm L on one section F of the supporting-axle is so organized as to drive a worm-wheel m on a longitudinal shaft M, mounted in suitable bearings in the frame, the section of this shaft sup-

porting the worm-wheel m being insulated in well-known ways, as indicated at m' , to prevent any current from passing through the 70 worm-wheel. Wipers or tappets $n n'$ on opposite sides of shaft M alternately strike corresponding tappets $o o'$ on opposite sides of a rock-shaft O, arranged crosswise of the frame and carrying contact-springs P P', which alternately come in contact with the opposite sections of the supporting-axle as the shaft is rocked in its bearings by the tappets, as described. The current passes through the frame E, through the rock-shaft and springs 80 alternately to the opposite sections of the supporting-axle, and through the wheel to the rail upon which the wheel is running, the rail for the time being acting as part of the working-circuit. A coil-spring p, secured at one end 85 to the motor-frame and at the other to the rock-shaft O, serves to keep one of the springs always in contact, unless separated therefrom by the tappets, thus assuring a passage of the current at all times.

90 The circuit-shifting mechanism shown in Figs. 4 and 5 breaks the circuit more slowly than that shown in Figs. 1 and 2, besides being more complicated.

Another and still simpler organization is 95 shown in Fig. 7, in which the supporting-axle F is shown as divided and insulated, as in Fig. 1. The supporting-wheels G G' are diametrically divided, so that the half of one wheel in front of the axle is insulated so as 100 to be non-conducting, while the corresponding portion of the opposite wheel constitutes a conductor, and the part behind the axle is insulated or non-conducting. The opposite sides of the motor are also insulated from 105 each other, as shown, except at their front ends. The contact-springs are mounted on opposite sides of the motor-frame and bear directly on the corresponding insulated sections of the axle. Under this organization 110 the current is shifted alternately from side to side, accordingly as the insulated or conducting section of the supporting-wheels rests upon the rail.

115 The operation of the apparatus will readily be understood from the foregoing description.

What I claim herein as of my own invention is—

1. The combination, substantially as hereinbefore set forth, of a stationary generator 120 of electric currents, a propelling rail-circuit, a return signal rail-circuit, a signaling-instrument therein, a vehicle supported on wheels on all three rails, an electromotor mounted thereon, and circuit-shifting mechanism on the motor-vehicle which shifts the current automatically from one to the other of the return-circuits.

2. The combination, substantially as hereinbefore set forth, of a generator, a rail constituting one branch of a propelling-circuit, rails constituting a return signaling-circuit, a signaling-instrument therein, a vehicle 130 electrically connected with all three of the

rails, an electromotor on the vehicle, and circuit-controlling mechanism on the motor-vehicle which automatically shifts the current from one return-circuit to the other 5 through the motor.

3. The combination, substantially as hereinbefore set forth, of the central propelling-rail, the lateral return-circuit rails, the vehicle, the motor-wheel running directly on the 10 propelling-rail, the partly-insulated supporting-wheels running on the return conducting-rails, the automatic circuit-shifting mechanism on the motor, the stationary generator,

the indicating mechanism at the central station, and the circuit-connections whereby the 15 current passes through the central rail and motor-wheel to the shifting mechanism on the motor-frame, which alternately shifts the current through the opposite supporting-wheels and return-circuit rails, as set forth. 20

In testimony whereof I have hereunto subscribed my name.

CHARLES H. RUDD.
